UNITED STATES PATENT OFFICE.

JOHN E. POWELL, OF AUGUSTA, GEORGIA.

FLUID-PRESSURE CYLINDER AND PISTON.

1,095,926.

Specification of Letters Patent.

Patented May 5, 1914.

Application filed December 3, 1913; Serial No. 804,479.

To all whom it may concern:

Be it known that I, JOHN E. POWELL, a citizen of the United States, residing at Augusta, in the county of Richmond and State of Georgia, have invented new and useful Improvements in Fluid-Pressure Cylinders and Pistons, of which the following is a specification.

This invention relates to improvements in fluid pressure cylinders and pistons for use in connection with any preferred type of apparatus operated by air, steam or other fluid pressure, the object of the invention being to provide a telescopic construction of cylinder and piston which is adapted to collapse in close compass and which is adapted to be extended to secure a desired length of travel, such construction of cylinder and piston being of value where the space is limited at the starting point and where the use of a collapsible fluid pressure power device is a factor.

A further object of the invention is to provide a telescopic cylinder and piston which is simple, reliable and comparatively inexpensive of construction, which is so constructed as to maintain the collapsible sections in rigid alinement when extended, and which is adapted to effectually cushion the inward movement of said collapsible sections.

The invention consists of the features of construction, combination and arrangement of parts herein fully described and claimed, reference being had to the accompanying drawing in which:—

Figure 1 is a vertical section of my improved telescopic cylinder and piston as it appears when the piston is extended to the full extent. Fig. 2 is a similar view of the cylinder and piston showing the parts in collapsed condition. Fig. 3 is a detail view of the bottom cylinder head and cushioning element. Fig. 4 is a detail section through one of the piston sections, showing the packing gasket.

Referring to the drawing, 1 designates the cylinder, which is provided at its base with a flange 2, to which is detachably secured a bottom head 3 having a flange 4 abutting against the flange 2, bolts 5 passing through said flanges and securing said bottom head in position. The body of the bottom head is offset downwardly to provide a counter-sink or concavity 6 having a beveled marginal wall 7, said cavity receiv-

ing a cushioning element 8, adapted to sustain the impact of the downward, closing or collapsing movements of the piston sections. This cushion may be made of rubber, or other suitable material, and is herein shown in the form of a disk having a beveled surface 9 contacting with the beveled wall 7, whereby undue enlargement of distention of the cushioning element is prevented.

The piston comprises a head or inner member 10, to which is connected the piston rod 11, and one or more outer hollow or tubular sections, two of which are shown in the present instance and designated 12 and 13, respectively. The upper end of the cylinder 1 and upper end of each of the piston sections 12 and 13 is provided with an annular inturn abutment flange 14, while the lower end of each of said cylinder sections 12 and 13 is provided with an out-turned annular abutment flange 15. The piston 10 when moved upwardly is adapted to engage the flange 14 of the section 12, and the flanges 15 of the section 12 is adapted to engage the flange 14 of the section 13, while the flange 15 of the section 13 is in turn adapted to engage the flange 14 of the cylinder 1, whereby the outward movements of the respective sections of the pistons are limited and said sections adapted to be coupled to each other on its outward movement to extend or raise the piston to the limit of its upward movement. The cylinder is provided with a fluid pressure inlet 16 opening through its bottom head, and in practice suitable valve controlled supply and exhaust connections are employed to regulate the flow of fluid pressure to and from the cylinder and piston sections. These fluid supply and exhaust connections are not herein shown, as they constitute no part of the present invention. When the piston is collapsed, as shown in Fig. 2, the sections telescope within each other and are inclosed wholly within the cylinder 1, and the lower abutment portions thereof contact with the cushioning member 8, which sustains the downward impact as each cylinder section reaches the limit of its downward travel, thus reducing all jars and concussions. The abutment flanges of the cylinder and piston sections are of sufficient area to stay and rigidly support the piston sections and prevent wobbling thereof when said piston sections are extended, as will be readily understood.

It will be apparent from the foregoing

that the construction described insures a desirable long range of travel of the piston from an initial or starting point, where the piston occupies an extent considerably less than its range of travel. The piston member 10 and flange 15 of each piston section 12 and 13 is provided with suitable packing, preferably comprising a leather packing ring 17 clamped and held against its bottom face by a clamping ring 18 secured to the piston member by screws 19. The outer peripheral edge of the ring 18 lies some distance inwardly of the periphery of the portion of the piston member to which it is attached and the free edge 20 of the gasket or packing ring 17 projects beyond and is adapted to fold back over the periphery of said packing ring to contact with the wall of the cylinder or coöperating piston section and effect a fluid tight joint. The portion 20 of the packing ring is adapted to be held pressed against the surface against which it is designed to bear or by means of a spring 21 seated within a groove 22 in the periphery of the ring 18. Vent openings 23 are provided in the cylinder and each of the intermediate piston sections for the purpose of permitting of the exhaust of any air confined between the engaging portions of the cylinder and pistons when the piston is raised, which ports are closed against the ingress of air when the piston is extended, but permit of the entrance of air when the piston collapses to avoid the formation of a partial vacuum.

From the foregoing description, taken in connection with the drawings, the construction and operation of my improved cylinder and telescopic piston will be readily understood, and it will be seen that the invention provides a device of this character which is simple, reliable and inexpensive of construction, and which at the same time is designed to secure an easy and stable motion of the

parts while cushioning all shocks and jars, 45 the advantages of which will be apparent.

I claim:—

1. A fluid pressure power device comprising a cylinder, and a piston comprising a plurality of telescopic sections, adapted to be extended beyond and to collapse within said cylinder, said cylinder and piston sections being provided with means for limiting the outward movements of said piston sections, and means for cushioning the inward movements of said piston sections.

2. A fluid pressure power device comprising a cylinder, and a piston comprising a plurality of telescopic sections adapted to be extended beyond and to collapse within said cylinder, said cylinder and piston sections being provided with abutment surfaces to limit the outward movements of said piston sections and with air exhaust passages coating with said surfaces, and means for cushioning the inward movements of said piston sections.

3. A fluid pressure power device comprising a cylinder having a bottom head provided with a concavity therein, a piston composed of a plurality of telescopic sections, said cylinder and piston being provided with coöperating abutments to limit the outward movements of said piston sections and co-acting air release ports controlled by said abutments, packing rings on the abutments of the piston sections, said piston sections being adapted to be extended from and to collapse within the cylinder, and a cushioning element seated in the concavity of the bottom head of the cylinder to cushion the closing movements of said piston sections.

In testimony whereof I affix my signature in presence of two witnesses.

JOHN E. POWELL.
